DESIGN AND CONSTRUCTION OF JIGS
AND FIXTURES

John Wharton, St. Albans, England; Alice Mary Wharton, executrix of the estate of said John Wharton, deceased, assignor to Wharton & Wilcocks Limited, Hertford, England.

Filed Nov. 3, 1959, Ser. No. 850,738
2 Claims. (Cl. 33—174)

This invention relates to the design and construction of jigs and fixtures.

In the specification to Patent No. 2,676,413 there is described and claimed a jig or fixture for use in the manufacture and production of component elements to accurate dimensions, such jig or fixture being built up of a multiplicity of interchangeable standard elements each furnished with one or more T-slots, or one or more tenon-slots, or one or more tenons or any combination of T-slots, tenon slots or tenons adapted to locate and secure the said standard elements relatively to one another and to a base or to a frame or frames attached to said base, on which they are mounted and secured to form a complete unitary structure. Among the standard elements described in the aforesaid specification is a so-called "angle setting unit" which comprises two parts, namely a circular base part having on its lower face a tenon, tenon slot or the like, by means of which it may be secured to a base member or to other standard elements such as so-called "stop elements," which normally play an important part in the construction of a jig or fixture, and a body part similar in form to a stop element but provided on its inner or under face with a female spigot adapted to receive a male spigot provided on the base part, the connection between the two parts being such that the body part may be axially rotated with respect to the base part. The base part is provided with graduations around its perimeter, and a zero mark for setting purposes is provided on the body part. In use the two parts are secured together and to a base member or other standard element by a bolt passing centrally through them.

Rigidity between the base part and the body part depends to a large extent upon the friction between them and the base member or other standard element on which they are mounted, and in some circumstances the relative setting of the parts may be disturbed, for example by a sudden severe accidental blow. The present invention has for its main object to minimise or obviate this disadvantage and to this end according to this invention it is proposed to provide means adapted to be secured to the body part of an angle setting unit and to a base member on which the unit is mounted, either directly or indirectly through the intermediary of other standard elements, whereby the rigidity of the setting of the parts of the unit is ensured.

Preferred features of this invention will be apparent from the following description and the appended claims.

In the accompanying drawing:

FIGURE 1 shows in plan and in side elevation respectively two typical applications of one form of means in accordance with this invention,

FIGURE 2 shows a third application thereof,

FIGURE 3 shows another form of means in accordance with this invention for giving a fixed angle setting, and

FIGURE 4 shows yet another form for giving a plurality of different fixed angle settings.

In FIGURE 1 two angle setting units are shown, each comprising, as previously stated, a circular base part 1 and a body part 2. Means for ensuring the rigidity of any relative angular setting of these two parts comprises

2

a plate 3 having an elongated slot 4 formed therein. The plate 3 is of generally T-shape, and the head thereof is apertured at each side for the reception of bolts 5 which are adapted to engage in a T-slot 6 in the side of the body part 1 (as is more clearly shown in FIGURE 2), thereby securing the plate 3 and body part 1 together. The plate 3 is secured to, for example, a base plate 7 by means of a bolt 8 passed through the slot 4 and into a T-slot 9 in the base plate 7. As the aperture 4 is elongated the bolt 8 merely has to be applied where this aperture coincides with the T-slot 9 in the base plate.

To support the plate 3 away from the base plate one or more cylindrical elements 10 may be passed over the stem of the bolt 8.

When the axis of the angle setting unit is parallel to the face of, for instance, a base member (see FIGURE 2), the setting of the body part 2 may result in a slotted plate 3 secured thereto being disposed at an angle to the face of the base plate 7. To secure the end of the slotted plate in this case a swivel unit 11 is provided, this unit having a tenon 12 for locating it in a T-slot in the base plate, being firmly secured thereto by a bolt 13. A swivel element 14 carried by a fitted pin 15 is provided with a screwed rod 16 adapted to be engaged in the slot 4 of the plate 3, securing nuts 17 being provided on the rod for engaging the plate on opposite sides thereof.

If desired two opposed slotted plates (as actually shown in FIGURE 2) may be secured to the body part 2 of the angle setting unit, a separate swivel unit 11 being associated with each.

In some cases it is proposed to utilise for the body part of an angle setting unit a stop element 2a as hereinbefore referred to (see, for example, FIGURE 3). In such cases the base part 1a would have tenon slots 20, as shown (or tenons), in its upper and lower faces. The tenon slot in one face is disposed at a fixed angle to the tenon slot in the other face, one serving to locate the base part 1a with respect to, for instance, a base plate 7, and the other serving to locate the body part 2a with respect to the base part 1a. With such an arrangement the setting of the body part 2a with respect to the base part 1a is, of course, fixed, and to cater for different angular settings a range of base parts would be provided, each with the tenon slots (or tenons) in the opposed faces thereof at a different angle.

It may not be convenient to provide such a range of base parts covering all angles that may be required and to reduce the actual number necessary for practical requirements modifications are provided as shown in FIG. 4.

With reference to FIGURE 4, the base part may be constituted by two circular elements, 1b, 1c each adapted to receive a common spigot or bush 30, the arrangement being such that the two elements can be rotated with respect to each other about such spigot or bush. Each element of the base part has a tenon slot 31 on its under face and a tenon slot 32 in its upper face, the angular relationship between the tenon slots in each element being varied to a given degree. The elements are adapted to be located with respect to each other and to, for instance, a base member by loose tenons 33. The angular relationship between the tenon slots in the two elements, which is known, enables the body part 2a of the angle setting unit to be set at an angle which is in effect an addition or subtraction of the angles between the tenon slots in the two elements of the base part. If desired more than two elements may be used for the base part.

Instead of a single tenon slot in the upper face thereof each element 1b, 1c of the base part may have (as is actually shown) two tenon slots 32, 33a crossing at right angles. A series of such elements would each have a single tenon slot on the lower face thereof, these tenon

slots being arranged at different angles some varying in clockwise direction and some anti-clockwise. By this arrangement any degree or fraction of a degree setting may be obtained, by the addition or subtraction of the angles represented by a number of base elements.

Thus, for example, a series of individual angle base elements, both clockwise and anti-clockwise, with angular relationship between tenon slots of $\frac{1}{2}^\circ$, 1° , $1\frac{1}{2}^\circ$, 2° , $2\frac{1}{2}^\circ$, 3° , $3\frac{1}{2}^\circ$, 5° , $7\frac{1}{2}^\circ$, 15° , $22\frac{1}{2}^\circ$, 30° , 37° with one at 45° will provide any angle from 0° to 45° in $\frac{1}{2}^\circ$ increments. In other words the total number of such base elements required would be twenty-seven.

The provision of the crossing tenon slots 32, 33^a in the upper faces of the base elements permit further variations in setting, actually covering a full scale from 0° to 360° in $\frac{1}{2}^\circ$ increments.

With the various arrangements described above rigidity of the setting of an angle setting unit can be ensured, that is either through the additional anchorage provided by the slotted plate or plates 3, or through the circular base element or elements 1^a, 1^b, 1^c. In the case of the latter, a stop element mounted thereon may be interlocked therewith by means of a tenon element 34, adapted to engage in the slot 33^a in the upper face of the uppermost base element 1^c disposed at right angles to the slot in which is engaged the tenon 33 on the underside of the stop element.

I claim:

1. A unit for use in constructing the frame-work of a jig or fixture to position a work-piece above a base having a flat face formed with a plurality of equally spaced parallel T-slots extending lengthwise in the upper face of the base, which unit comprises interchangeable rings each having a first tenon slot in its underface, tenon means removably engageable in a T-slot of said base and the first tenon slot of a selected ring for orienting the selected ring with respect to a slot in the base, each ring also having a second tenon slot in its upper face disposed at a respective fixed angle to said first tenon slot, the fixed angles of respective rings differing from each other, a block of polygonal section adapted to be mounted on the selected ring on the base and having a flat lower end engageable with the upper face of the selected ring, tenon means operatively associated with said block and engageable in said second tenon slot of the selected ring thereby to determine fixedly the angular relation-

ship between the block and the ring, and means for securing the block and the selected ring to the base.

2. A unit for use in constructing the frame-work of a jig or fixture to position a work-piece above a base having a flat upper face formed with a plurality of equally spaced parallel T-slots extending lengthwise in the upper face of the base, which unit comprises plural rings each having a tenon slot extending diametrically of its under face and also having a pair of tenon slots extending diametrically of its upper face perpendicular to each other and at a selected fixed angle to the tenon slot in the under face of the ring, the fixed angles of respective rings differing from each other, tenon means engageable in the tenon slot in the under face of a first selected ring and in a slot in the upper face of the base for locating and fixedly orienting a selected first ring with respect to the base; tenon means engageable in the tenon slot in the under face of a second selected ring and in one of the tenon slots in the upper face of said first selected ring for locating and orienting the second ring with respect to the first ring, whereby, by proper selection of a first and second ring having respective fixed angles, a predetermined orientation between the tenon slots in the upper surface of said second ring and the slots in the upper face of said base may be obtained, a block of polygonal section having a flat lower end adapted to engage the upper face of the second ring and having a T-slot extending longitudinally of at least one side thereof perpendicular to said lower end, tenon means engageable in such last named T-slots and in one of the tenon slots in the upper face of said second ring to orient said block with respect to the tenon slots in the upper face of said second ring, and means operable to secure the said block and said two rings to said base, with the angular relationship between the tenon slots and the two rings serving to determine the angular setting of said block.
